Attorney

UNITED STATES PATENT OFFICE.

SPURGEON GAGE, OF MOUNT HERMON, MASSACHUSETTS.

RADIATOR AIR VALVE.

Application filed October 14, 1924. Serial No. 743,601.

To all whom it may concern:

Be it known that I, SPURGEON GAGE, a citizen of the United States, residing at Mount Hermon, in the county of Franklin and State of Massachusetts, have invented certain new and useful Improvements in Radiator Air Valves, of which the following is a specification, reference being had to the accompanying drawings.

10 This invention relates to valves, particularly those used in connection with steam radiators for the purpose of permitting escape of air therefrom, and has for its object the provision of a valve having an extension which projects into the radiator beyond the inner wall thereof so as to permit the exhaust of air from the radiator while preventing water of condensation from being blown out with the air and falling upon 15 the floor as is an ordinary occurrence with the ordinary type of valve.

An important and more specific object is the provision of a valve of this character in which the extension is concaved so that 25 water of condensation running down the radiator wall will travel along the extension to the center of the concaved portion and drop off instead of ever reaching the end and mixing with the air.

30 An additional object is to provision of a device of this character which will be simple and inexpensive to make, positive in action, efficient and durable in service, and a general improvement in the art.

35 With the above and other objects and advantages in view, the invention consists in the details of construction to be hereinafter more fully described and claimed, and illustrated in the accompanying drawings in 40 which:

The figure is a longitudinal section through the valve showing it extending through the wall of a fragment of a radiator.

45 Referring more particularly to the drawing, the letter A designates a portion of the wall of an ordinary radiator such as is used in dwelling houses or, in fact, any other buildings having steam heating plants. The 50 valve indicated at B may itself be of any ordinary or preferred construction though in the present instance it is represented as comprising a casing 10 having a stem 11 screwed through the wall A and formed

with a bore 12 leading to a valve seat 13 55 normally engaged by the conical end 14 of a valve 15 screwed through the outer portion of the casing and equipped with a knob or handle 16. This type of valve is old and well known and no claim is made for the 60 construction thereof. It should also be understood that the particular type shown is for purposes of illustration only, as any other type of valve might be used instead.

The essence of the invention lies in the provision of an extension 17 on the threaded portion 11 of the valve, which extension projects considerably into the radiator or beyond the inner face of the wall A thereof, the bore 12 passing, of course, through 70 this extension. The periphery of the extension 17 is provided therearound with a continuous groove or channel 18 having its base wall at all points concaved in a direction lengthwise of the extension 17 with 75 the central low portion of the groove or channel relatively deep, said groove or channel extending to the outer or free end of the extension 17 and to the wall A when the valve is applied.

In the use of the device it is apparent that the drops of water C formed by condensation of steam on the radiator wall will fall upon the extension 17 and drop off without ever reaching the end of the extension, the 85 concaved or channeled shape of the extension positively preventing the water from reaching the end. Obviously, the water cannot mix with and be blown out with the air passing through the passage or bore 12 when 90 the valve is opened and in this way it is evident that spilling of the water on the floor or surrounding objects in a building will be avoided.

While I have shown and described the 95 preferred embodiment of the invention and have illustrated a specific type of valve and a certain shape and size for the extension, it should be understood that I reserve the right to make many changes and variations 100 in the details provided such modifications will constitute no departure from the spirit of the invention or the scope of the claim hereunto appended.

Having thus described the invention, I 105 claim:

In combination with a wall of a radiator having an air vent for the radiator, a pro-

jection at the vent extending into the radiator and having a port formed as a continuation of the vent, the projection having a groove or channel disposed entirely around the periphery thereof, said groove at all points being concaved in a direction lengthwise of the projection, said groove extend-

ing from the wall to the outer end of the projection, the central low portion of the groove being relatively deep.¹⁰

In testimony whereof I hereto affix my signature.

SPURGEON GAGE.
